Hermann Triest Inventor

By Henry Schreiter, his Atty.

UNITED STATES PATENT OFFICE.

HERMANN TRIEST, OF NEW YORK, N. Y.

REVERSIBLE HANDLE-MOUNTING FOR BRUSHES.

SPECIFICATION forming part of Letters Patent No. 624,708, dated May 9, 1899.

Application filed February 2, 1899. Serial No. 704,276. (No model.)

To all whom it may concern:

Be it known that I, HERMANN TRIEST, of the city, county, and State of New York, have invented certain new and useful Improvements 5 in Reversible Handle-Mountings for Brooms, of which the following is a full, clear, and exact specification, reference being had to the accompanying drawings, wherein—

Figure 1 is a plan view of the base-plate; 10 Fig. 2, a similar view of the handle attachment; Fig. 3, an elevation of the bolt used for affixing the handle attachment to the base-plate. Fig. 4 is an elevation, partly a sectional view, of the complete device secured 15 to the back of a broom. Figs. 5, 6, and 7 are views similar to Figs. 2, 3, and 4, respectively, illustrating a modified construction of the device.

Similar letters of reference indicate corresponding parts in all views of the drawings. 20

My invention relates to street-cleaning appliances; and it consists of the hereinafter-described reversible handle-mounting for brooms for street-sweeping and for similar 25 utensils.

In sweeping the streets the brooms are used always in one direction only and their bristles are used upon the side—namely, opposite to the handle—while they remain in good 30 serviceable condition on the other side.

The object of my invention is to provide a cheap and serviceable mounting for handles of brooms and facilitating the reversing of the handle without detaching the base-plate from 35 the back of the broom.

The mounting consists of base-plate A, (illustrated in Fig. 1,) provided with bores e for affixing it to the back D of the broom by means of screws e', handle attachment B, 40 (shown in Fig. 2,) and bolt C (shown in Fig. 3) for securing the two other parts together.

The base-plate A is provided with a screw-threaded bore c in its center and with raised portions a, having their edges d parallel to 45 each other and equidistant from bore c. The recess between these raised portions a is fitted to receive the tongue b of the handle attachment, having a bore c' in corresponding position to the bore c of the base-plate and 50 sufficiently large to receive the shank of the bolt C. The thread of the screw-bolt corresponds with that of the bore c, and by screw-

ing bolt C into the base-plate the flange f of the screw-bolt is pressed upon the tongue b of the handle attachment and holds it between the raised portions a and locks the parts firmly together. 55

It will be observed that bolts C and F are shown to have caps g on the ends of their shanks. These caps are made by hammering the ends of the bolts after they are screwed in the base-plate to prevent removing of the bolts from the base-plate. 60

By unscrewing bolt C tongue b is sufficiently loosened to be raised above the level of the raised portions a of the base-plate, and then the handle may be reversed by turning the handle attachment B on bolt C and set in opposite direction. Then the parts of the mounting are again fastened together by 65 screwing bolt C into plate A. The changing of the broom-handle from one side to the other is thus readily and easily accomplished by merely unscrewing the bolt C, then switching the handle to the other side, setting tongue 70 b in place, and screwing down the bolt. The handle is then as firmly and securely affixed to the broom and in proper position as when it was originally mounted thereon. 75

In the modified construction illustrated in 80 Figs. 5, 6, and 7 a wedge-bolt F is used in place of the screw-bolt C. Wedge-bolt F consists of a screw-threaded shank j and an oval-shaped wedge k, situated below the flange f' and integral therewith. Tongue b of the handle attachment B is provided with an oval aperture c², corresponding in shape to the wedge k and slightly larger to permit the tongue b to be lifted closely to the flange f' when the wedge-bolt F is turned and the 85 wedge k brought in line with aperture c c of the tongue. When tongue b is thus lifted from the recess between the raised portions a of the base-plate, the handle can be turned around or reversed in the same manner as 90 explained above with reference to the other construction, and when tongue b of the handle attachment B is again put in place between the raised portions a of the base-plate and wedge-bolt F is turned from left to right 95 wedge k is brought across aperture c c, whereby the handle is secured firmly to the broom. The tongue b of the modified construction of 100 my improved handle-mounting is flat and

even, the same as that of the construction shown in Figs. 1 to 4; but owing to the shank *j* being screw-threaded the wedge *k* is pressed upon it in the same manner as if the surface 5 of the tongue *b* be an inclined plane. The advantage of this modified construction is that it does not require more than a quarter of a turn of the bolt *F* to release and fasten the handle attachment to the back of the 10 broom, whereas in the previously-described construction the screw-bolt *C* must be turned several times around to permit reversing of the handle. Both constructions, however, are well adapted for the attainment of the 15 object of this invention. They can be cheaply produced, are of great practical use, and easily applicable to the broom.

I claim as my invention and desire to secure by Letters Patent—

- 20 1. A reversible mounting for handles of brooms and similar utensils comprising a base-plate adapted to be secured to the back of the broom, a screw-threaded bore in center of the base-plate and raised portions, having 25 parallel edges, situated equidistantly from and on both sides of the screw-threaded bore, a handle attachment having a tongue fitted between the edges of the raised portions of the base-plate and provided with a bore cor-

responding in position to the bore of the base-plate, a bolt having a screw-threaded shank fitted into the bore of the base-plate and provided with means for retaining the tongue of the handle attachment. 30

2. A reversible mounting for handles of 35 brooms and similar utensils comprising a base-plate adapted to be affixed to the back of a broom and having a screw-threaded bore in its center and raised portions, having parallel edges, set equidistantly from and on both 40 sides of the screw-threaded bore; a handle attachment, having a tongue fitted in the recess between the raised portions of the base-plate and an oval aperture in position corresponding with the bore of the base-plate, and 45 a wedge-bolt, consisting of a screw-threaded shank, an oval-shaped wedge, fitted into the aperture of the tongue, and a handle, the wedge and the handle being integral with the shank of the bolt. 50

In witness that I claim the improvements described in the foregoing specification I have signed my name in the presence of two subscribing witnesses.

HERMANN TRIEST.
